CLAIM

The ornamental design for an antenna, as shown and described.

DESCRIPTION

FIG. 1 is a perspective view of an antenna showing our new design;

FIG. 2 is a front view of the antenna as shown in FIG. 1;

FIG. 3 is a rear view of the antenna as shown in FIG. 1;

FIG. 4 is a right side view of the antenna as shown in FIG. 1;

FIG. 5 is a left side view of the antenna as shown in FIG. 1;

FIG. 6 is a top view of the antenna as shown in FIG. 1; and,

FIG. 7 is a bottom view of the antenna as shown in FIG. 1.

The broken line showing of the indicia on the surfaces of the front and rear faces of the antenna and the broken line showing of the mounting stem are included for the purpose of illustrating a portion of the antenna and forms no part of the claimed design.

AirWire is registered mark of Pinyon Technologies.
